UNITED STATES PATENT OFFICE.

JAMES P. APPLEBY, OF HOPKINS, MINNESOTA.

ELECTRICAL SWITCH.

No. 855,494.

Specification of Letters Patent.

Patented June 4, 1907.

Application filed April 8, 1905. Serial No. 263,432.

To all whom it may concern:

Be it known that I, JAMES P. APPLEBY, a citizen of the United States, residing at Hopkins, in the county of Hennepin and State of Minnesota, have invented certain new and useful Improvements in Electrical Switches; and I do hereby declare the following to be a full, clear, and exact description of the invention, such as will enable others skilled in the art to which it appertains to make and use the same.

My invention has for its object to provide an improved lock attachment for the switch of electric igniting apparatus, such as used on automobiles, launches, and elsewhere, in connection with explosive engines.

To the above ends, the invention consists of the novel devices and combinations of devices hereinafter described and defined in the claims.

In the accompanying drawings, which illustrate my invention, like characters indicate like parts throughout the several views.

Figure 1 is a view in front elevation, showing a switch in which is incorporated the several features of my invention. Fig. 2 is a side elevation of the parts shown in Fig. 1, showing also, by dotted lines, a key applied in working position; and Figs. 3 and 4 are views in front elevation, with the lock case removed, showing the improved switch, and illustrating different positions of the parts thereof.

The numeral 1 indicates a block of insulating material, which forms a support for the several parts of the switch and lock attachment.

The numerals 2, 3 and 4 indicate metallic contacts secured on the face of the block 1, and forming terminals respectively of lead wires 2^a, 3^a and 4^a. As shown, the contact 2 is located near the top of the block 1, while the contacts 3 and 4 are located near the bottom thereof, directions being taken with respect to the block set in the position shown in the drawings. For the purposes of illustration, it should be assumed that a set of dry cells or batteries are connected in circuit with the leads 2^a and 3^a, that a magneto or dynamo is connected in circuit with the leads 2^a and 4^a, and that the electrodes of the igniter (not shown) are connected in both of said circuits.

The switch lever 5 is pivoted at 6 on a trunnion located, as shown, approximately at the center of the block 1, with freedom for

movement either into engagement with the contact 3 or 4, at the will of the operator, and it is preferably provided at its free end with a finger piece 7. At its opposite side, 60 and quite near to its pivoted end, the switch lever 5 is provided with projecting lugs 8.

As is evident from what has been said, when the switch lever 5 is thrown to its left into engagement with the contact 3, the batteries will be thrown into a closed circuit with the electrodes of the igniter, while, on the other hand, when said lever is thrown to the right, into engagement with the contact 4, the dynamo will be connected in circuit 70 with the electrodes of the igniter.

The lock may be of any suitable form, and in the drawings only the tumbler 9, and a case section 10 thereof, only are shown. The case section 10 is rigidly secured to the block 1, preferably by screws 11 having their heads concealed in the back of the block. A key 12 for operating the lock, fits in a slot or key seat 13 of the tumbler 9. The said tumbler is provided with a laterally projecting cam 80 lug 14 that works in a slot 15 of a sliding contact plate 16, which plate is countersunk into a seat formed in the face of the block 1, and is guided for straight line sliding movements, by said seat and by the trunnion 6, 85 which affords a pivot for the lever 5. On the contact plate 16 is a pair of short contact posts 17 that engage one with each of the lugs 8 of the switch lever 5.

The relation of the parts is such that whenever the switch lever 5 is turned into engagement with one of the contacts 3-4, one of its lugs 8, acting on one of the posts 17, will positively force the contact plate 16 into engagement with the contact 2, thereby closing 90 the circuit through one or the other of the two sources of electrical energy, according to the direction of movement of said lever. When, however, the lock tumbler 9 is, by the key 12, turned into the position indicated in Fig. 3, the contact plate 16 is moved out of engagement with the contact 2, and the posts 17, acting on the lugs 8 of the lever 5, force the said lever into an intermediate inoperative position, and positively lock the 100 same in such inoperative position, so that no amount of force applied to said lever will serve to move it from such inoperative position, or to move the contact plate 16 into engagement with the contact 2. The locking of the contact plate 16 when the tumbler 9 and cam lug 14 are turned into the position

shown in Fig. 3 is due to the fact that any upward force applied to the said contact plate will be resisted with a direct end thrust by said cam lug. Otherwise stated, the said tumbler and cam lug can be moved from the position shown in Fig. 3 into the position shown in Fig. 4 only by the use of the key and can not be given such movements by force applied thereto by an attempt to move the switch lever 5 while the said cam is in the said position shown in Fig. 3. The lock mechanism (not shown, but which, as already stated, may be of any approved construction, such, for instance, as a Yale lock), will, of course, prevent movement of the tumbler 9, except by the use of the proper key. Hence it of course follows that, under the conditions above noted, the switch lever is held in an inoperative position in such manner that it cannot be tampered with, thus rendering it impossible to start the engine. It is also evident that the switch lever cannot possibly be locked in an operative position, since the locking movement of the lock tumbler positively forces the said lever into its inoperative position. This feature is of great importance. It is, of course, a well-known fact that with Yale locks, and all locks of that general character, the key can be applied to the lock or removed therefrom only when the tumbler of the lock is turned to a predetermined normal position. Hence, it will of course be understood that the key can not be removed from the lock when the tumbler is turned into the position shown in Fig. 4 of the drawings.

From what has been said, it will be understood that the device described is capable of modification within the scope of my invention, as herein set forth and claimed. The device may, of course, be applied to an electric igniter having but a single circuit and a single source of electrical energy.

What I claim and desire to secure by Letters Patent of the United States is as follows:

1. In a device of the character described, the combination with leads having terminal contacts, of a switch lever and a sliding contact plate and having engaging parts coop-

eratively arranged to close and break the circuit between said contacts, and a key-operated lock having a tumbler arranged to move said sliding plate into an inoperative or circuit breaking position, and to lock the same in such position, and which contact plate, in turn, operates on said switch lever, to force the same into an inoperative position, and to lock the same, substantially as described.

2. In a device of the character described, the combination with leads having terminal contacts, of a pivoted switch lever and sliding contact plate co-operatively arranged to close and break the circuit between said contacts, said lever having laterally projecting lugs, and said plate having co-operating lug-engaging projections operating, when said plate is moved into a circuit-breaking position, to force said lever into an inoperative position, and a key-operated lock having a tumbler formed with a projecting cam lug operating on said contact plate, to force the same into a circuit-breaking position, and to lock the same, and said lever, substantially as described.

3. In a device of the character described, the combination with an insulating block and three lead wires having terminal contacts 2, 3, and 4, of a switch lever 5 pivoted to said block and movable into engagement with said contacts 3 and 4, and having laterally projecting lugs 8, the sliding contact plate 16 mounted in said block, movable into and out of engagement with said contact 2, and provided with projections 17 acting on said lugs 8, to force said lever 5 into an intermediate inoperative position, and a key-operated lock having a tumbler 9 formed with a cam lug 14 working in a seat 15 of said contact plate 16, and operating thereon to force said contact plate into a circuit-breaking position, and to lock the same, and said lever, substantially as described.

In testimony whereof I affix my signature in presence of two witnesses.

JAMES P. APPLBY.
